ANCHOR MEMBER FOR LOAD BRACINGS

Alfred P. Kivlin, North Attleboro, Mass., assignor
to H. J. Forster, as trustee for Association of
American Railroads

Application March 5, 1935, Serial No. 9,357

1 Claim. (Cl. 72—105)

The invention relates to the bracing of loads in the load carrying compartments of freight cars or similar vehicles wherein it is desired to secure the load against shifting during transit, and the primary object of the invention is to provide anchor members which will enable an efficient temporary bracing of the above character to be readily and economically applied and removed, and avoid the likelihood of injury to the walls of the compartment, or to the operative in applying and removing the bracing. Further objects and advantages of the invention will be in part obvious and in part specifically referred to in the description hereinafter contained which, taken in conjunction with the accompanying drawing, discloses suitable ways of carrying the same into effect; such disclosure, however, is to be regarded merely as illustrative of the principles of the invention. In the drawing—

Fig. 1 is a perspective view of the interior of a freight car compartment having load bracings applied thereto in accordance with the invention.

Figs. 2 and 3 are also perspective views illustrating somewhat more ramified ways of carrying out the invention.

Fig. 4 is a plan view of one form of face plate adapted to be used in carrying out the invention.

Fig. 5 is a section on line 5—5 of Fig. 4.

Fig. 6 shows a simple form of anchor which may be conveniently used to engage the ends of lengths of flexible metal strapping detachably with face plates of the form shown in Figs 4 and 5.

In Fig. 1 the invention is shown as applied to the bracing of a load 1 against the end wall 2 of a freight car compartment. The side walls 3 and 4 of the car are shown as provided with a plurality of fixtures or anchor members constructed in accordance with the invention. These fixtures or face plates are permanently set into the walls of the compartment and lengths 7 of flexible metal box strapping are detachably engaged in suitable manner (one device suitable for the purpose being later described in detail) with conveniently located face plates 6. The lengths of strapping 7 thus anchored to the compartment, are then tightened up with respect to the load 1 to be braced, and tied in tightened position. In the form shown in Fig. 1, what may be termed the central ends of the lengths 7 of strapping overlap across the inner face of the load 1, and may be tightened up by means of tensioning mechanisms such as are already known and available in the box-strapping art, and a seal 8, also as heretofore

employed in the box strapping art, may be applied by such mechanism to tie the tightened lengths of strapping together; or if the strapping be in the form of wires, wire-tying mechanisms as known in the art may be employed for the above mentioned tensioning and tying purposes. Fig. 1 shows two bracings of the character above described, applied to the load at different levels.

To disconnect the bracing it is merely necessary to cut the strapping 7 which is so inexpensive that it may be thrown away and new lengths employed for bracing the next load to be carried. Once the tension on the strapping is released, it may be readily disengaged from the fixtures or face plates 6, leaving the latter in proper condition to receive the next strapping to be applied. These fixtures 6 constitute the only permanent bracing equipment, and the operations of installing and removing the bracing therefore are simple and inexpensive, and avoid the likelihood of injury to the walls of the compartment, such as frequency has happened in the past where temporary bracings of a make-shift character have been nailed to the walls of the compartment with the likelihood of injury thereto, as well as to the operatives or the material being shipped.

Fig. 2 shows a somewhat more ramified form of applying the invention wherein lengths 7a of flexible metal strapping are engaged at one end with the fixtures 6 and tied at their remaining ends to a 30 metal rod 9, to which latter supplementary pieces of strapping 7b are then secured at one end. The ends of the pieces of strapping 7b may then be passed around the load to be braced and engaged with similar pieces of strapping (not illustrated) coming from the opposite side wall of the car, and tightened and tied in the same manner as is above described in respect to the inner ends of the strapping 7 shown in Fig. 1.

Fig. 3 illustrates another somewhat more ramified application of the invention which is particularly useful in refrigerator cars and other constructions in which the face plates 6 should be confined to certain restricted locations, in order to avoid impairment of special wall constructions such as the insulation used in refrigerator cars. In Fig. 3 two of the face plates 6 are shown at the right attached to the door frame of the car, and two more adjacent the ice bunker 2a at the end of the car. Lengths of strapping 7c may then be attached, for example, to the upper face plates 6 of Fig. 3, having their adjacent ends tied together by a seal 8a similar to the seal 8 above described, in such manner that the composite piece of strapping thus formed lies substantially

parallel to a wall of the car. A supplementary piece of strapping 7d may then be tied to the lengths 1c (as by a similar seal 8b) at any point suitable and convenient for the particular load to be braced. The supplementary piece of strapping 7d may then be passed around the load, tensioned, and tied to a similar piece of strapping (not illustrated) coming from another wall of the car, in a manner similar to that above described in connection with the inner ends of the lengths of strapping 7 shown in Fig. 1.

The particular form of face plate shown in Figs. 4 and 5 is adapted to be set into a wall of the compartment so that its face lies substantially flush, and is permanently secured in such position by suitable fastening devices such as screws, bolts or rivets (not illustrated) passing through the holes 10 in the face plate. A T-shaped slot 11 is provided in the face plate 6 in such manner that its side walls 12 overlie a recess 13 in the fixture. And for the purpose of engaging the flexible metal strapping 7 in the fixture, an anchor 14 may be attached to the end of strapping 7 and inserted through the head of the T-shaped slot 11, and locked underneath the overhanging walls 12, when tension is applied to the strapping 7 in a right hand direction as the face plate appears in Figs. 4 and 5. This anchor 14 may be, for example, a plain piece of metal rod around which one end of the strapping 7 is passed and secured in place by one or more seals 8c similar

to the seal 8b above described. The particular form of the attachment between the face plate and the strapping however is not essential.

While certain particular ways of carrying out the invention have been described it should be understood that changes may be made therein without departing from the invention in its broader aspects within the scope of the appended claim.

I claim:

An anchoring fixture for flexible metal box strapping comprising a face plate constructed to be attached to a wall, said fixture being provided with a recess located behind the face plate of a width to receive an anchor member attached to the strapping, said face plate having one slot 15 affording passage of an anchor member therethrough into said recess and a second slot at an angle to the first slot and communicating therewith, an anchor member receivable into said recess through the first mentioned slot and slidable 20 along the inner walls of the face plate which define the second mentioned slot, the fixture having an end wall extending angularly inward from the face plate adjacent the second slot, said end wall being positioned to abut the anchor member 25 when the latter is slid along in the recess as aforesaid, and box strapping passing through the second mentioned slot and connected to said anchor member.

ALFRED P. KIVLIN. 30
